CLAIM

The ornamental design for a cleaning apparatus as shown and described.

DESCRIPTION

FIG. 1 is a perspective view of a cleaning apparatus showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view with the lid open thereof;

FIG. 10 is an enlarged view of portion of FIG. 1;

FIG. 11 is an enlarged view of portion of FIG. 1; and,

FIG. 12 is an enlarged view of portion of FIG. 1.

The broken lines in the drawings are for the purpose of illustrating portions of the cleaning apparatus and form no part of the claimed design. The dot-dash broken lines in the drawings indicates cutoff boundaries for the enlarged detailed portion views and form no part of the claimed design.
